PULVERIZED FUEL BURNER

Application filed May 19, 1927. Serial No. 192,635.

This invention relates to fuel burners of the type in which pulverized fuel mingled with air is injected directly into a furnace.

Various types of burner have been proposed for burning pulverized fuel and in these there is inherent the ever present problem of providing a uniform distribution of the coal around the periphery of the burner pipe and causing it to mingle uniformly with the air which is supplied for combustion. The present invention relates to a burner of the type in which the pulverized fuel is initially mingled with a portion of the air required for its combustion, and is then projected into the furnace within an annulus of secondary air. One of the bothersome problems has been to keep the fuel and the primary air properly mixed so that there will be a uniform distribution of the fuel into the surrounding layer of secondary air within the furnace. It is ordinarily necessary to conduct the pulverized fuel within circuitous or tortuous passages extending from the storage bin or the pulverizer to the burner, because of the cramped space within the average furnace room. The velocity in these passages has to be high in order to prevent the fuel from being deposited therein, and wherever the mixture of fuel and primary air passes around a bend in the conducting pipe, the coarser particles of fuel are necessarily segregated to some extent, because of the action of centrifugal force, and pass along that portion of the pipe which has the curve of greater radius. Various devices have been proposed for mixing the coal and primary air but these have involved difficulties in the matter of producing a satisfactory distribution of the material around the inner periphery of the burner pipe at the point where it issues into the furnace combustion space.

It is accordingly the main object of this invention to provide a burner of this type for pulverized fuel which is of very simple construction and may be easily manufactured and readily installed in cramped quarters in a furnace room, which will serve efficiently to maintain the fuel and primary air properly distributed within the burner pipe around

its periphery, and which will cause this fuel to mingle with the secondary air and be substantially uniformly distributed thereto.

With these and other objects in view, as will be apparent to those skilled in the art, our invention resides in the combination of parts set forth in the specification and covered by the claims appended hereto.

In accordance with this invention, we provide a furnace burner which has a burner pipe arranged to project the pulverized fuel and primary air through an opening in a furnace wall, and deflectors to distribute the secondary air around the outside of the primary burner pipe, and we provide the burner pipe with a baffling structure so constructed that the fuel will be uniformly distributed around its inner periphery just before issuing into the furnace and into contact with the secondary air. The baffle structure is so arranged in the pipe that it changes the direction of movement of the heavier particles of fuel which tend to segregate as they pass around bends in the pipe and so causes the heavier and the lighter particles of fuel to mix with one another. This is accomplished closely adjacent to and in direct line with the end of the burner and preferably near distributing vanes which are provided to throw the fuel outwardly in every direction into the ring of secondary air surrounding the burner pipe. The deflectors for introducing the secondary air provide a uniform distribution and cause the air to whirl, thus aiding in the production of a thorough mixture and rapid combustion.

Referring more particularly to the drawings which illustrate one embodiment of our invention, and in which like reference numerals indicate like parts:

Fig. 1 is a vertical section through a burner, the section being taken on the line 1—1 of Fig. 2;

Fig. 2 is a section on the line 2—2 of Fig. 1; and

Fig. 3 is a perspective view of a mixing baffle.

The embodiment of our invention illustrated in the drawings comprises a vertical furnace wall 10, constructed of suitable re-

fractory material, and provided with an opening 11 therethrough which is preferably circular as shown. A plate 14 may be suitably attached to the outside of the wall, surrounding the opening, and arranged to act as a support for other parts of the burner. A heavy ring 15, with an internal diameter equal to that of the opening 11, may be bolted to the furnace side of the plate 14 to act as a stiffening member, and to form a ledge which assists the brick mason in constructing the circular refractory arch forming the opening.

A horizontal cylindrical fuel pipe or nozzle 18 is mounted adjacent to the furnace wall and arranged to project a stream of pulverized fuel and primary air centrally through the opening 11 into the furnace. This stream is derived from any suitable source of supply, such as a storage bin or a pulverizer of the so-called unit type, and is fed to the burner through a connecting pipe. It is customary to have a pipe elbow 20 bolted to the outer end of the pipe 18, and this elbow may be mounted at various angles about the axis of the pipe so as to provide a convenient connection to the source of supply of fuel and primary air.

In order to supply secondary air uniformly around the fuel nozzle to the opening 11, we provide a series of guide vanes or deflectors 25 spaced evenly around the nozzle, and preferably arranged tangentially as illustrated so as to cause a whirling motion of the entering air. These vanes may be conveniently constructed by first forming a hollow cylinder 26 of sheet metal, cutting three sides of each vane therein, and then bending the vanes inwardly to the angle desired. The cylinder 26 may be suitably attached to the plate 14 by means of the angle shaped members 28. With the burner illustrated, the air is drawn inwardly between the deflectors by the suction of the furnace, this suction being maintained either by the natural draft of the stack or by the action of an induced draft fan. It is apparent that in case it is desired to utilize forced draft with this burner, it is merely necessary to provide a casing to form a pressure chamber around the outside of the deflectors. As it is advisable to provide means for controlling the size of the openings between the deflectors and thereby permit operation at various ratings, we arrange outside the cylinder 26 a cylindrical damper 30, which may be rotated to the desired point by handles 31. This damper should be arranged to close in the direction of the arrows in Fig. 2, so as to cause the air to flow along the vanes and maintain its whirling motion even at the lower ratings.

A vertical closing plate 35 is mounted at the front of the burner and together with the cylinder 26 forms a casing to prevent the entrance of secondary air except between the 65 deflectors. In order to prevent injury to this

plate from the radiant heat of the furnace, we prefer to arrange a flat shield 36 on the furnace side of the closing plate. This shield may be constructed of any suitable material, such as cast iron, and it is provided with perforations 37 as illustrated to eliminate cracking due to expansion. If desired, a small door 38 may be provided to cover an opening through the plate and shield, thus permitting observation of the flame, or the insertion of a torch for igniting the fuel stream.

The deflectors 25 bring about an even distribution of secondary air around the fuel nozzle 18, and in order to obtain uniform combustion conditions and a symmetrical flame it is essential to deliver the fuel evenly to this secondary air. This problem is rendered difficult because of the segregation which invariably occurs in the pipe line leading to the burner. The coarse particles of fuel tend to separate from the fines by gravity even in a straight pipe, and when there are bends or elbows in the pipe line, as is usually the case, this separation is greatly aggravated by the action of centrifugal force. In order to eliminate this segregation, we provide within the fuel pipe a transverse plate or narrow annular baffle 45 having a circular orifice 46 therein substantially smaller in diameter than the pipe. This plate presents a deflecting surface to any segregated portion of the fuel traveling close to the pipe wall. While this orifice or baffle plate may be flat, we prefer to construct it in the form of a hollow frustum of a cone, as illustrated, which produces less resistance to the flow. The presence of the plate 45 is thought to cause great turbulence and violent eddy currents in the fuel stream, whereby the coarse and fine particles are thrown together and a thorough mixture produced. If the plate is shaped as illustrated, the frustum is preferably arranged to converge towards the discharge end of the pipe in the direction of the stream travel, and serves as a sloping baffle along which coarse particles may slide and so be thrown into the burner pipe at an angle to the axis thereof, thus causing them to be distributed more uniformly in the air current. This baffle is preferably located near the outlet or burner end of the pipe so that there will be no opportunity for the coarse particles to segregate again before they enter the furnace. This plate should on the other hand be spaced somewhat from the discharge end of the fuel nozzle, as illustrated, so that the mixing operation may take place fully before the fuel issues into the furnace, but this space should not be excessive nor should any pipe bends occur therein, for under those conditions all advantages obtained from the use of the plate will be lost. The plate 45 may be conveniently mounted, as shown, by providing thereon a flange 48 which is held

between the elbow 20 and the closing plate 35. A hollow cylindrical extension 50 on the furnace side of the flange 48 provides a convenient arrangement for supporting the pipe 18, which is held therein.

5 As it is desirable to produce a rapid and thorough mixture of fuel and secondary air within the furnace, resulting in complete combustion and a short flame, we provide adjacent to the discharge end of the fuel nozzle 10 a suitable spreading device 55. In the embodiment illustrated, this comprises a sheet metal structure having a large number of small inwardly extending vanes 56, each arranged at an angle to the fuel flow. The stream of primary air and fuel strikes these vanes, and is thrown outwardly in all directions with a whirling motion into the surrounding secondary air, producing a condition 15 of extreme turbulence. We have found that under most conditions the results obtained are better if the direction of whirl of the fuel is opposite to that of the secondary air, though under some circumstances it may 20 be preferable to whirl them both in the same direction. In order to avoid impingement of the flame on the refractory surfaces of the opening 11 and the slagging condition which would result therefrom, we construct this 25 opening so as to flare outwardly on the side toward the furnace as shown at 58.

The operation of our invention will now be apparent from the above disclosure. A whirling stream of secondary air is delivered 30 by the deflectors 25 to the opening 11. A stream of pulverized fuel and primary air is brought to the elbow 20 from a pulverizer or storage bin, and the segregation in this stream is destroyed by the action of the orifice plate 45, which produces a uniform mixture 35 within the pipe 18. This mixture strikes the vanes 56 near the exit end of the pipe, and is thrown outwardly with a whirling motion into the surrounding secondary air. Each vane 56 tends to produce a small 40 localized stream of a mixture rich in fuel. These small streams have a rate of flame propagation much higher than that of the remaining mixture, and as a result they form 45 a plurality of small pilot lights, which maintain ignition close to the burner and produce a short flame. Combustion is also accelerated by the heat which is reflected on to the issuing fuel stream from the surrounding 50 incandescent refractories at 58.

Having thus described our invention, what we claim as new and desire to secure by Letters Patent is:

1. In a furnace having a wall provided with 60 a burner opening, a burner for pulverized fuel comprising a central imperforate fuel pipe smaller than the opening mounted adjacent to the opening and arranged to discharge therethrough a stream of pulverized fuel and primary air, means including a series

of deflectors arranged uniformly around the pipe to direct a whirling stream of secondary air through said opening around the outside of the fuel stream, an annular orifice plate mounted within the pipe and spaced from its discharge end, said plate being arranged to present a deflecting surface to any segregated fuel traveling close to the pipe wall, and means adjacent to the discharge end of the pipe for throwing the fuel outwardly into the secondary air. 70

2. A burner for pulverized fuel comprising a central imperforate fuel pipe mounted adjacent to a furnace and arranged to discharge into said furnace a stream of pulverized fuel 80 and primary air, means including a series of deflectors arranged uniformly around the pipe to direct a whirling stream of secondary air into the furnace, an annular orifice plate mounted within the pipe and spaced from its discharge end to present a narrow deflecting surface in the path of any segregated fuel traveling along the pipe wall, and a spreading device adjacent to the discharge end of the pipe and arranged to whirl the fuel stream 85 and throw it outwardly into the secondary air. 90

3. In a furnace having a wall provided with a circular burner opening, a burner for pulverized fuel comprising a central cylindrical fuel pipe arranged to discharge a stream of pulverized fuel and primary air through the opening means including a series of deflectors arranged uniformly around the pipe and substantially parallel thereto 95 so as to direct a whirling stream of secondary air through the opening and outside the fuel stream, damper means for controlling the flow of secondary air through said deflectors, an orifice plate in the form of a hollow frustum of a cone mounted within said pipe and spaced from the discharge end thereof, and a plurality of vanes extending across the discharge end of the pipe and each arranged at an angle to the fuel flow so as to throw the 100 fuel outwardly in a whirling stream into the secondary air. 105
